UNITED STATES PATENT OFFICE.

WINTHROP MURRAY CRANE, OF DALTON, MASSACHUSETTS.

MACHINERY FOR MANUFACTURING ORNAMENTAL PAPER.

SPECIFICATION forming part of Letters Patent No. 293,229, dated February 12, 1884.

Application filed July 5, 1883. (No model.)

To all whom it may concern:

Be it known that I, WINTHROP MURRAY CRANE, a citizen of the United States, residing in Dalton, in the county of Berkshire and State of Massachusetts, have invented a new and useful Improvement in Machinery for Manufacturing Ornamental Paper, of which the following is a specification.

My invention relates to certain improvements in mechanism or apparatus for effecting the printing or coloring of paper during the process of manufacture. Prior to my invention the coloring had been effected by dyeing the pulp before forming the same into paper, and liquid colors had in some cases been applied to the unsolidified pulp web before the same had been pressed or dried. The web had also been superficially dyed by completely immersing the same in a colored liquid size after having been pressed and dried.

My invention consists in an improved mechanism or apparatus whereby coloring material is applied to either or both surfaces of the continuous web of paper after the same has been solidified and the greater part of its moisture expelled by its passage through the press-rolls of the paper-machine, and I am thereby able to apply one or more colors by a continuous process upon a portion or upon the whole of either or both surfaces of the paper, and to imprint upon the paper in this manner designs or figures of any kind. My improved machinery is therefore not only well adapted for manufacturing paper for bank-notes, drafts, checks, certificates, passage-tickets, and similar vouchers in which it is necessary or desirable to guard against fraudulent removal of written or printed characters upon the surface of the paper, or the falsification of figures, letters, or characters upon the same, but it is also applicable to the manufacture of ornamental, striped, figured, or colored paper for any purpose for which such paper is commonly employed.

In the drawings I have shown a portion of a paper-making machine embracing the parts necessary to enable my improvements to be understood, in which—

Figure 1 shows, in elevation, a portion of such machine, together with the mechanism which I employ for applying the colors to the

paper. Fig. 2 is a front view of said mechanism, and Fig. 3 is a modification adapted for printing in more than one color.

In applying my invention I prefer to combine it with an ordinary paper-making machine—such, for example, as the well-known Fourdrinier machine. The pulp is prepared and refined in the usual manner, being afterward diluted with water and formed into a continuous sheet or web upon an endless wire cloth or apron, whence it is transferred to a felt blanket, still in a green and unsolidified condition. This blanket conveys the web to a series of two or more pairs of press-rolls, by which it is consolidated and compressed and the greater part of its moisture expelled. The terminal pair of rolls of these series is shown at A A in Fig. 1 of the drawings, which represents a part of the well-known Fourdrinier machine. In the ordinary process of paper-making, the web *w*, after emerging from the press-rolls, is next conveyed directly by an endless belt to the first of a series of steam-heated hollow drying-cylinders B C, &c., which revolve slowly by power and serve to gradually dry the paper as it passes along and around them in the direction indicated by the arrows in the figure.

The apparatus for printing or coloring the paper according to my invention may be mounted upon the frame F of the Fourdrinier machine at a point between the press-rolls A A and the first drying-cylinder, B. This apparatus is shown in elevation or end view in Fig. 1 and in an enlarged front view in Fig. 2. It consists of a cylinder, G, which may be termed the "color-roller," and which is so mounted that its lower portion is immersed, as it revolves, in a coloring liquid or die, *d*, contained in a suitable reservoir, D. The color-roller G is caused to revolve by means of a pulley, *g*, to which motion may be imparted from a belt or gearing connected to any convenient portion of the moving machinery. A printing-roller, H, is mounted in bearings or journals above the color-roller G, and may receive its motion therefrom by friction. It is important that the periphery of this color-roller G, and consequently that of the printing-roller H, should move at precisely the same speed as the periphery of the press-rolls A A, so that

the web of paper *w* will pass uniformly through the printing mechanism without longitudinal strain. Above the printing-roller is placed a small jockey-roller, *I*, which should be caused 5 to press, by means of springs or otherwise, toward the printing-roller *H*. The web of paper *w* in its passage through the machine, as indicated by the arrows, is led between the printing-roller *H* and the jockey-roller *I*, and 10 hence when the machine is in operation the coloring-matter is taken by the printing-roller *H* from the color-roller *G* as it revolves, and is continuously transferred to or imprinted upon the undermost surface of the web of paper *w*.

In illustration of the process, I have shown in Fig. 2 a simple form of printing-roller adapted to produce a design consisting of a series of longitudinal parallel colored stripes upon the 20 paper web. It is evident that a great variety of other and different designs may be produced in the same manner simply by varying the design upon the surface of the printing-roller *H*. If a plain printing-roller is 25 used, without any design whatever upon its surface, a uniform tint of any required color may be imparted to the paper.

By using variously-grooved rollers—such as shown in the drawings—any required number 30 of parallel stripes may be imprinted upon the paper, and by employing a divided roller or two or more separate rollers, *G*, *G'*, upon the same axis, as shown in Fig. 3, each revolving in a separate compartment of the reservoir *D*, 35 supplied with different coloring materials, different colors may be applied simultaneously. Ornamental designs—such as national flags, handkerchiefs, or the like—may be engraved upon the surface of the roller *H*, and at each 40 revolution of the latter they may be transferred in one or more colors to the paper web as it passes through the machine.

In case it is desired to apply color or imprint designs on both sides of the paper, I 45 make use of a second set of rollers, as shown at *G'*, *H'*, and *I'*, so that the web *w*, after passing the first drying-cylinder, *B*, and thus drying the color first applied, may be led over the roller *C'*, and thence between the second printing- 50 roller, *H'*, and the second jockey, *I'*, and finally over the roller *C*, to the second drying-cylinder, *C*, and so on through the machine in the usual manner.

It is obvious that any special ornamental 55 design or pattern engraved upon the printing-roller *H* will be repeated upon the web at every revolution of the said roller. A cutting-machine may be so adjusted in connection with

the Fourdrinier machine that sheets will be automatically cut off from the continuous web 60 after sizing and drying, so that each separate sheet will contain one copy of the design imprinted upon the roller, which design will appear on one or both sides of the sheet, as the case may be.

By applying the color in the manner hereinbefore described—that is to say, after the web has been pressed and the greater part of its moisture expelled—it will not penetrate far enough into the fiber of the paper to spread 70 laterally and become spotted or indistinct; nor can writing be fraudulently erased therefrom without exposing the inner fibers of the paper, and thereby changing its apparent color. By the use of my invention paper may 75 be ornamented in any desired way by the application of designs and colors during the process of manufacture at trifling cost.

I claim as my invention—

1. In a paper-making machine, the combination, substantially as hereinbefore set forth, of the press-rollers, the drying-cylinders, and the color-printing roller revolving in contact with the paper web between the press-rollers and the drying-cylinders.

2. In a paper-making machine, the combination, substantially as hereinbefore set forth, of the press-rollers, two or more drying-cylinders, and two color-printing rollers, one of the latter revolving in contact with the paper web 90 at a point between the press-rollers and the drying-cylinders, and the other in like manner at a point between two drying-cylinders.

3. In a paper-making machine, the combination, substantially as hereinbefore set forth, of the press-rollers, the color-roller, the printing-roller, the jockey-roller, and mechanism, substantially such as described, whereby the periphery of the printing-roller is caused to move at the same rate of speed as the periphery of the press-rollers.

4. In a paper-making machine, the combination, substantially as hereinbefore set forth, of the press-rollers, the drying-cylinders, the printing-roller, the divided color-roller, and 105 the reservoir of coloring material divided into compartments corresponding to the divisions of said color-roller.

In testimony whereof I have hereunto subscribed my name this 26th day of June, A. D. 110 1883.

WINTHROP MURRAY CRANE.
